Letters Patent No. 1277 - Dated July 3, 1860.

The schedule referred to in these Letters Patent and making part of the same.

To whom it may concern:

I, Samuel H. Ransom, of the City of Albany, and State of New York, have produced a new ornamental design for a Cooking Stove, and I, hereby declare that the annexed delineations are full and accurate representations of the ornamented parts and their several ornaments.

The plates not represented, being similar to their corresponding plates and similarly and symmetrically ornamented.

What I claim as my production and desire to secure by Letters Patent, is the combination and arrangement of ornamental figures and forms represented on the accompanying drawings forming together the ornamental design for a Cooking Stove.
